UNITED STATES PATENT OFFICE

135,609

DESIGN FOR A HOUSE

Arthur T. Brown, Tucson, Ariz.

Application March 5, 1943, Serial No. 109,678

Term of patent 14 years

To all whom it may concern:

Be it known that I, Arthur T. Brown, a citizen of the United States, residing at Tucson, in the county of Pima and State of Arizona, have invented a new, original and ornamental Design for a House, of which the following is a specification, reference being had to the accompanying drawings, forming part thereof.

I claim:

The ornamental design for a house, as shown.

ARTHUR T. BROWN.
